UNITED STATES PATENT OFFICE

123,305

DESIGN FOR A CALCULATOR OR SIMILAR ARTICLE

Alan W. Crowell, Longmeadow, Francis L. Merritt, West Springfield, and Kenneth H. Pond, Longmeadow, Mass.

Application January 6, 1940, Serial No. 89,334

Term of patent 14 years

To all whom it may concern:

Be it known that we, Alan W. Crowell, Francis L. Merritt, and Kenneth H. Pond, citizens of the United States, residing at Longmeadow, West Springfield, and Longmeadow, respectively, in the county of Hampden and State of Massachusetts, have invented a new, original, and ornamental Design for a Calculator or Similar Article, of which the following is a specification, reference being had to the accompanying drawing, forming part thereof.

Fig. 1 is a plan view of a calculator or similar article showing my new design.

Fig. 2 is a side elevational view of the same.

We claim:

The ornamental design for a calculator or similar article, substantially as shown.

ALAN W. CROWELL.
FRANCIS L. MERRITT.
KENNETH H. POND.
